UNITED STATES PATENT OFFICE.

JOSEPH STEVENSON, OF ESSENDON, VICTORIA.

COMBINED LATCH AND LOCK.

SPECIFICATION forming part of Letters Patent No. 638,604, dated December 5, 1899.

Application filed July 5, 1899. Serial No. 722,849. (No model.)

To all whom it may concern:

Be it known that I, JOSEPH STEVENSON, builder, a subject of the Queen of Great Britain and Ireland, and a resident of 3 Agatha 5 street, Essendon, in the Colony of Victoria, have invented a certain new and useful Combination Latch and Lock, (for which I made application for provisional protection in Victoria, dated and filed February 28, 1899, and 10 numbered 15,942,) of which the following is a specification.

The object of my invention is to provide a cheap yet effective lock for doors and other purposes which shall have but few parts. 15 These, though not liable to derangement, are of such a simple character that they can be easily assembled. Only one bolt is used, which acts for both latching and locking the door, and the key instead of throwing the bolt simply 20 operates an eccentric. It is either a right or a left hand lock and only a handle-hole (no keyhole) has to be made through the door.

Referring to the drawings which form a part of this specification, Figure 1 represents 25 a perspective view showing the interior of the lock with one of the handles and the plates of the shell removed. The driving-key is in the keyway in the follower and is operating the same, and the door is therefore latched. 30 Fig. 2 shows the lock in section attached to a door. The driving-key is not operating the follower, and the door is therefore locked. Fig. 3 is a perspective view, on a smaller scale, 35 of the key. Fig. 4 is a perspective view of the spring, one end of which is attached to the bottom of a collar. Near its middle it is forced outwardly by an eccentric-rod, hereinafter described. The driving-key is not protruding from the circumference of the collar, 40 but is in grooves therein.

Similar letters of reference indicate similar or corresponding parts where they occur in the several views.

A is the lock-shell, through which passes a 45 tubular spindle B, that also passes through the door and is capable of rotating in either direction. On either end of and secured to the spindle are the knobs C. In the center of the hollow spindle B and capable of rotation therein 50 in either direction is a rod or cylinder D, Fig. 2, hereinafter called the "eccentric-cylinder," which has an eccentric portion E, against

which bears the inner end of a radially-movable slide-block H', that passes through holes in the spindle and in the collar J, surrounding 55 and secured to the spindle within the casing. The outer end of this slide H' bears against the inner side of a spring G, which is curved partly around the collar J, and one end of the spring is secured to the bottom of the collar by a rivet K, while its other free end transfixes a slide or locking-dog M. Spring G is so bent that it always tends to force the dog M inward until the spring and dog are forced outwardly by the slide H' in a manner hereinafter described. The dog M travels backward and forward in radial grooves in the sides of plates or flanges L of collar J. The collar J is surrounded by a circular yoke N, which is provided with radial lugs P P, 70 adapted to engage studs Q Q on the arms R R of the bolt-frame. When the dog M is forced outwardly until its outer end engages in the keyway O in the yoke N, the bolt S can be moved by rotating spindle B. 75

From the foregoing it will be seen that when the hollow spindle B is turned and the dog M is in the keyway O of the yoke N, as shown in Fig. 1, the bolt S can be withdrawn. The bolt is returned and kept "shot" by the bolt-spring T, as usual. When the eccentric-cylinder is turned in one position, the eccentric E forces slide H' outward, thereby causing spring G to force dog M into engagement with slot O in yoke N, and then the yoke N will 80 turn with the spindle and the device can be used as a latch. When the eccentric E is turned to the opposite position, the spring G forces slide H' inward and withdraws dog M from slot O, so that the yoke will not turn 85 with the spindle and the device will be locked. 90

To lock the door, the eccentric-cylinder D is properly turned inside the hollow spindle by passing a key V through one of the key-holes in the knobs C. The door-key is flat, 95 as shown, (though it may be of any section,) and has at its inner end two projections W. There are also on its sides two or more recesses or bays which agree with wards made around the internal circumference of the 100 ward-cylinders X within the spindle. The ward-cylinders extend from the ends of the eccentric-cylinder D to the cap-pieces Y and prevent the longitudinal movement of the ec-

centric-cylinder D therein. The number, conformation, and disposition of the wards in these cylinders will vary with conditions. When the eccentric is in the position as shown 5 in Fig. 2, the door is locked, since the spindle can rotate without moving the follower.

As shown in Fig. 1, the yoke N has a third arm E, which is adapted to bear against an abutment A' on the bolt-frame and prevent 10 the bolt being prized backwardly by violent means. When, however, the yoke is operated by the dog M locking the collar to the yoke, the third arm is partially rotated out of the way of the said abutment.

15 The alarm attachment consists of a striking plate or ring B', secured to the hollow spindle or to one of the faces of the collar J. Upon this are the striking-arms C' C', which when the handle is rotated make contact 20 with one arm of the three-armed pivoted lever D'. This lever is situated beneath the bell-spring E', above which is the bell-push F', connected to the hammer of a bell G', attached to the door or to the lock.

25 The operation of my lock is as follows: When used as a latch, the bolt is normally, as in all locks, shot; but when it is desired to lock the door the bolt is prevented from being withdrawn by the third arm shown 30 and the key V is inserted and the spindle turned until the eccentric E has permitted spring G to disengage dog M from yoke N. The spindle can then rotate without in any way affecting either the yoke or the bolt, but 35 it rings the bell, and thereby either alarms the burglar or burglars or informs those inside that some one desires to enter.

Having thus described my invention, what I therefore claim as new, and desire to secure 40 by Letters Patent thereon, is—

1. The combination of a rotatable spindle, a collar thereon, a yoke surrounding the said collar, a radially-movable dog adapted to lock said yoke to the collar, and a curved spring 45 attached to said collar adapted to withdraw the said dog from the yoke, and devices within the spindle whereby it can cause the spring to throw said dog into engagement with the yoke.

50 2. The combination of a rotatable spindle, a collar thereon, a yoke surrounding the said collar, a radially-movable dog adapted to lock said yoke to the collar, and a spring attached to said collar adapted to withdraw the said 55 dog from the yoke, an eccentric within the spindle, and a radially-movable slide operated by said eccentric adapted, when the eccentric is in one position, to cause the spring to throw said dog into engagement with the 60 yoke.

3. The combination of a rotatable spindle, an eccentric therein, a yoke surrounding the spindle and adapted to engage and operate

the bolt-frame; a bolt-frame provided with lugs adapted to engage arms on the yoke, and 65 an arm on said yoke adapted to prevent the retraction of the bolt when the yoke is disengaged from the spindle; with a dog for locking said yoke to the spindle, and devices operated by said eccentric for controlling the 70 position of said dog.

4. The combination of the spindle, the eccentric therein, the ward-cylinder within said spindle adapted to be locked to the eccentric by a key, the yoke surrounding said spindle, 75 a radially-movable dog adapted to lock the said yoke to the spindle, means for moving said dog inward, and means controlled by the eccentric for moving the radial dog outward, 80 substantially as described.

5. The combination of the spindle, the eccentric therein, the ward-cylinders within said spindles adapted to be locked to the eccentric by a key, the yoke surrounding said spindle, a radially-movable dog adapted to lock 85 the said yoke to the spindle, means for moving said dog inward, and means controlled by the eccentric for moving said dog outward; with a bolt-frame adapted to be operated by lugs on said yoke, and an arm on said yoke 90 adapted to positively lock the bolt when the sliding dog is disengaged from the yoke.

6. The combination of the spindle, the eccentric therein, the ward-cylinder within said spindle adapted to be locked to the eccentric 95 by a key; a flanged collar attached to the spindle, the curved spring attached to said collar, the sliding plate playing through the spindle and interposed between the eccentric and said spring, the yoke surrounding said 100 collar, and the dog mounted on said spring adapted to be engaged with said yoke when the sliding plate is projected by the eccentric.

7. The combination of the spindle, the eccentric therein, the ward-cylinder within said 105 spindle adapted to be locked to the cylinder by a key; a flanged collar attached to the spindle, the curved spring attached to said collar, the sliding plate playing through the spindle, interposed between the eccentric and 110 said spring, the yoke surrounding said collar and the dog mounted on said spring adapted to be engaged with said yoke when the sliding plate is projected by the eccentric, with the 115 sliding-bolt frame operated by said yoke, and an arm on said yoke adapted to positively lock the bolt-frame when the yoke is disengaged from the collar, substantially as described.

In witness whereof I have hereunto set my 120 hand in presence of two witnesses.

JOSEPH STEVENSON.
